UNITED STATES PATENT OFFICE.

WILLIAM H. GOODYEAR, OF WILKINSBURG, PENNSYLVANIA, ASSIGNOR OF
ONE-FOURTH TO D. KARCHER, OF WILKINSBURG, PENNSYLVANIA.

TROLLEY.

SPECIFICATION forming part of Letters Patent No. 721,794, dated March 3, 1903.

Application filed March 18, 1902. Serial No. 98,717. (No model.)

To all whom it may concern:

Be it known that I, WILLIAM H. GOOD-
YEAR, a citizen of the United States, residing
at Wilkinsburg, in the county of Allegheny
5 and State of Pennsylvania, have invented a
new and useful Improvement in Trolleys, of
which improvement the following is a speci-
fication.

This invention relates to certain new and
10 useful improvements in trolleys, and relates
more particularly to that class that will not
come off the wire or become accidentally dis-
engaged therefrom.

The invention has for its object the provi-
15 sion of novel means whereby a trolley-wheel
may be constantly engaged with the trolley-
wire and wherein an accidental displacement
of the same will be impossible; furthermore,
20 to provide novel means whereby the trolley-
wheel may be easily disengaged from the wire
when desired and properly operated.

With the above and other objects in view
the invention consists in the novel combina-
25 tion and arrangement of parts to be herein-
after more fully described, and specifically
pointed out in the claims.

In describing the invention in detail refer-
ence is had to the accompanying drawings,
30 forming a part of this specification, and
wherein like numerals of reference indicate
like parts throughout the several views, in
which—

Figure 1 is a side elevation of my improved
trolley as it appears when in actual use. Fig.
35 2 is a top plan view thereof. Fig. 3 is a per-
spective view of one of the sections of the
clamp in which the attachment is mounted.

In the drawings the reference-numeral 1 in-
40 dicates the trolley-pole, and 2 the trolley-
harp, and 3 indicates the trolley-wheel. The
trolley-wire is represented by the reference-
numeral 4.

Upon the trolley-harp 1 is secured a clamp
5, formed in two sections, forming a bracket
45 6, said bracket having openings 7 formed
therein to receive suitable fastening means,
such as nuts and bolts 8. Lugs 9 are formed
integral with each section of the bracket, and
in these lugs 9 openings 10 are formed, in
50 which the arms 11 are slidingly secured. At
the lower end of said arms 11 are provided

loops 12 to receive the operating cord or rope
14. Upon the arms 11 are also secured pins
15, which operate in curved grooves 16, com-
municating with the openings 10, formed in 55
the lugs 9. In order to give the arms 11 a
rotary movement when operated downwardly
by operating-cord 14, these arms 11 are en-
circled by spiral springs 17, the lower ends
of which rest against the upper face of the 60
brackets 9, and the upper ends of the spiral
springs bear against washers 18, which are
secured in position by means of nuts 19 upon
the screw-threaded portion 20 of the arms. 65
The upper ends of the arms 11 are bifurcated,
as shown at 21, to receive spring-pressed
fingers 22, these spring-pressed fingers being
curved inwardly, as shown at 23, and are nor-
mally retained in position by means of springs
24, forming a connection with the fingers 22 70
and arms 11.

The operation of my improved trolley is as
follows: The trolley being placed in position,
as shown in Figs. 1 and 2 of the drawings,
the arms and fingers will prevent the trolley-
75 wire disengaging the trolley-wheel and will
retain the same normally in the trolley-wheel
3. When it is desired to release the trolley-
wheel, the operating-cord 14 is drawn down-
wardly, thereby compressing the spiral spring 80
17, and the pins 15, riding in the grooves 16,
will partially rotate the arms 11, carrying the
fingers 22, and will open the same, allowing
the trolley-wire to be easily disengaged from
85 the wheel. As soon as the cord is released
the spring 17 will automatically close the
fingers to their former position. It will be noted
that an independent movement is also ob-
tained by the fingers 22.

The many advantages obtained by the use 90
of the improved trolley will be readily appar-
ent from the foregoing description, taken in
connection with the accompanying drawings.

It will be noted that various changes may
be made in the details of construction with-
95 out departing from the general spirit of my
invention.

Having fully described my invention, what
I claim as new, and desire to secure by Letters
100 Patent, is—

1. In a trolley, the combination of a bracket,
arms secured on said bracket, spring-pressed

fingers carried by said arms, and means whereby said arms and fingers are partially rotated, substantially as described.

2. In a trolley, the combination of a bracket, 5 arms slidingly secured in said bracket, springs surrounding the said arms, fingers pivotally secured at the end of said arms, springs connecting said arms and fingers, and an operating-cord secured to the end of said arms, all

parts being arranged substantially as described and for the purpose set forth.

In testimony whereof I have hereunto signed my name in the presence of two subscribing witnesses.

WILLIAM H. GOODYEAR.

In presence of—

JOHN GROETZINGER,
M. HUNTER.
